UNITED STATES PATENT OFFICE.

CHARLES E. GODLEY, OF DETROIT, MICHIGAN.

DESIGN FOR A LAMP DOOR.

Application filed August 24, 1923. Serial No. 7,078. Term of patent 7 years.

To all whom it may concern:

Be it known that I, CHARLES E. GODLEY, a citizen of the United States, residing at Detroit, in the county of Wayne and State of Michigan, have invented a new, original, and ornamental Design for Lamp Doors, particularly for the doors of automobile head lamps, of which the following is a specification, reference being had to the ac-

companying drawing, forming part thereof.

Fig. 1 of the drawing is a front elevation of a lamp door embodying my new design. Fig. 2 is an edge view of the door.

I claim:

The ornamental design for a lamp door, as shown.

CHARLES E. GODLEY.
